(57) **CLAIM**

We claim the ornamental design for the filter element, as shown and described.

DESCRIPTION

FIG. 1 is a perspective view of the filter element;
FIG. 2 is a partial perspective view thereof;
FIG. 3 is a top view thereof;
FIG. 4 is a side view thereof;
FIG. 5 is a side view thereof showing the side opposite that shown in FIG. 4;
FIG. 6 is a bottom view thereof;
FIG. 7 is a front view thereof;
FIG. 8 is a back view thereof;
FIG. 9 is another perspective view of the filter element of FIG. 1; and,
FIG. 10 is a partial perspective view thereof.
The use of broken lines in the aforementioned figures is for illustrative purposes only. The features shown in broken lines form no part of the claimed design.

1 Claim, 7 Drawing Sheets

FIG. 3**FIG. 4**

FIG. 5**FIG. 6**

FIG. 8

FIG. 7
